BOTTLE RECEIVER

Alfred C. Kohl, Marshfield, and Philip F. Kohl,
Mosinee, Wis.

Application October 28, 1940, Serial No. 363,078

6 Claims. (Cl. 193—32)

The present invention relates to a device for receiving bottles and temporarily storing them at a point some distance from the place where they may be deposited in the receiver.

A problem encountered, particularly during busy periods, in bars and soft drink establishments is that a large number of empty bottles accumulate that are in the way and clutter up the back bar or the space in back of the counter.

The primary object of the present invention is to provide a device whereby bottles may be readily removed from a point of congestion and accumulated at another point where they can be later sorted and disposed of.

Another object of the invention is the production of such a device which is simple in construction and which handles the bottles without breakage.

Other objects and advantages of the invention will be apparent to those skilled in the art upon understanding the preferred embodiment thereof disclosed in the accompanying drawings. It is to be understood that the drawings are for purposes of illustration only and are not intended to limit the scope of the invention as it is defined in the appended claims as modifications may be made in the form, material employed in construction and arrangement of the parts without departing from the true spirit and scope of the invention.

With respect to the drawings:

Fig. 1 is a plan view of the device;

Fig. 2 is a sectional view taken on the line 2—2 of Fig. 1; and

Fig. 3 is a detailed sectional view taken on the line 3—3 of Fig. 2.

Referring to the drawings, the device consists of a bottle-receiving member 10 which may project from a wall or floor 11 and to which is attached a conduit 12 which provides a passageway for bottles. The shape of the receiving member 10 is shown as funnel-shaped for purposes of illustration but this shape may be modified to have a more aesthetic appearance. The conduit 12 may be a rubber tube of sufficient diameter to receive the bottles or a flexible metal tube or even a rigid conduit.

The conduit 12 has attached at the lower end thereof a trough portion 13 which continues the passageway for the bottles after they leave the conduit. In the drawings the conduit 12 is shown broken away from the trough 13 to indicate that either the trough or the conduit may be of considerably greater length in relation to the other than is indicated in the drawings.

The trough 13 is preferably rigidly mounted by means of a supporting member 14 which may be secured to the frame of the bottle distributing portion of the device, as indicated at 14a. Further support for the trough 13 is obtained through means of a strap 14b, the strap 14b being attached to some rigid member such as a portion of a building. Of course, additional straps or supports may be employed for the purpose of rigidly securing the trough 13.

An advantage of employing an open trough is that it is easy to clean and makes readily accessible the interior of the closed conduit 12 for cleaning purposes.

15 A bumper head 15 is provided at the end of the trough member 13. The bumper head 15 comprises a housing member which is preferably separated from the trough 13 which is so mounted that it may oscillate and provide a resilient shock-absorbing means for the bottles as they leave the trough 13.

The mounting means for the bumper head 15 consists of a pair of rollers 16 and 16a, respectively, that are secured by U-shaped members 17 and 17a to the top of the bumper head 15. The rollers 16 and 16a ride upon the supporting member 14 and permit the bumper head to oscillate and move lengthwise of the support 14. A spring member 18 yieldingly urges the bumper head toward the trough, the spring member being connected to the bumper head and to a tension-adjusting member 19 which member 19 is mounted on the supporting member 14 and is adjustable to vary the tension of the spring.

25 30 35 An adjustable stop 20 is provided on the support 14 to limit the movement of the bumper head 15 toward the trough 13. The bumper head member is provided with an end member 21 opposite the trough 13 which is preferably constructed of composition rubber or other resilient material. As the bottles strike the end member 21 they bounce back from that member and will engage the opposite end member 22 of the bumper head which member 22 is preferably cushioned to absorb the shock of the bottle striking the same. The bottle then drops down to the receiving tray 23 which is preferably conical in shape.

40 45 50 The center of the tray 23 may be formed from a wood block 24, the center of which block is provided with cushioning means which may be of rubber or other resilient material 25. The receiving tray 23 is supported by a framework consisting of a plurality of legs 26 attached by means of cross members 27 upon which are

mounted annular supports 28 and 29, respectively, which engage the underside of the receiving tray 23 and the block 24 to support the receiving tray throughout its area.

It is to be noted that the cushioning member 22 of the bumper head 15 is positioned beneath the trough 13 so as to give room at the top of the bumper head 15 for entrance of bottles as they pass from the trough 13. It is also to be observed that the lower edges of the side walls of the bumper head 15 adjacent the cushioning ends 21 and 22, respectively, are cut away so as to permit bottles to freely leave the bumper head and to turn in relation to the bumper head as they drop on to the receiving tray.

In the operation of the device the bottles are deposited in the receiving member 10, pass downwardly through the conduit 12 and trough 13 to the bumper head 15 which absorbs the shock of the bottles striking the head both through the resilient mounting of the bumper head and the cushioning means 21 and 22. As a bottle strikes the bumper head, the bumper head tends to oscillate and the bottle will fall upon the apex 25 of the receiving tray 23. Due to the oscillatory movement of the bumper head the bottles will strike the apex 25 of the receiving tray in various positions and at different points on the cushioning member 25 so that the bottles will roll in various directions over the receiving tray and be substantially equally distributed around the tray. Thus practically the entire surface of the tray may be used for the accumulation of bottles.

A further advantage of resiliently mounting the bumper head 15 is that since the mounting means absorbs part of the shock of the bottle after it enters the bumper head the bottle has no tendency to kick back into the trough and thus obstruct the passage of the next bottle, which might result in breakage. Furthermore, the absorption of the inertia of the bottle in the bumper head is so rapid that the bottles drop very quickly on to the receiving tray 23 and thus it is possible to insert bottles into the device in relatively quick succession without incurring the possibility of their jamming or breaking due to contact with one another.

The cone-shaped receiving member 23 being provided with a cushioning means at its center, the shock of the bottles' fall is absorbed sufficiently so that there is no breakage at this point. The taper of the cone of the receiving tray 23 is relatively gradual so that after the bottles drop upon the receiving tray they roll rather slowly to the periphery of the receiving tray. Thus, when the bottles come in contact with the edge of the tray or with other bottles already deposited their rate of motion is sufficiently slow so that there is no danger of breakage.

While we have shown and described the receiving tray as being circular, it is plain that it may be of many shapes. It is also apparent that the cushioning means at the apex of the receiving tray 23 may be made of any resilient material or other material which will not cause breakage of the bottles upon being dropped from the bumper head.

As is apparent from the foregoing description, the device is composed of relatively few parts

which are economical to manufacture and in actual practice the device has been found to be extremely useful and practicable.

We claim:

5 1. In a device of the class described, a passageway for bottles, a bumper head resiliently mounted at the end of said passageway, said mounting means permitting said bumper head to oscillate and to move axially in relation to said passageway and a receiving tray mounted beneath said bumper head.

15 2. In a device of the class described, a passageway for bottles, a bumper head resiliently mounted at the end of said passageway, said mounting means permitting said bumper head to oscillate and to move axially in relation to said passageway, and a receiving tray mounted beneath said bumper head, said receiving tray having a cone-shaped central portion immediately 20 beneath said bumper head.

25 3. In a device of the class described, a passageway for bottles, a bumper head mounted at the end of said passageway, said bumper head provided with shock absorber means to absorb the shock of bottles as they strike said bumper head, a second means for engaging the bottles positioned opposite said shock-absorbing means and a receiving tray mounted beneath said bumper head, said receiving tray having an apex 30 provided with resilient means upon which the bottles drop from said bumper head.

35 4. In a device of the class described, a passageway for bottles, a bumper head positioned at the end of said passageway, said bumper head having a closed top and downwardly projecting ends and side portions, said side portions being cut away at the lower ends thereof, the end of said bumper head opposite said passageway being provided with resilient means and the end of 40 said bumper head adjacent said passageway having an opening therein to permit passage of the bottles into said bumper head.

45 5. In a device of the class described, a passageway for bottles, a bumper head positioned at the end of said passageway, said bumper head having a closed top and downwardly projecting ends and side portions, said side portions being cut away at their lower ends, the end of said bumper head opposite said passageway being provided with resilient means and the end of said bumper head adjacent said passageway having an opening therein to permit passage of the bottles into said bumper head and projecting beneath said opening to engage the bottle after it 55 engages said resilient means, said bumper head being resiliently mounted at the end of said passageway and means positioned beneath said bumper head for receiving said bottles.

60 6. In a device of the class described, means constituting a passageway for bottles, shock-absorbing means slidably mounted at the end of said passageway, means for receiving bottles after engagement with said slidably mounted shock-absorbing means and resilient means for urging 65 said slidably mounted shock-absorbing means toward the lower end of said passageway.
